GUN BLAST DOOR

George Bussiere, Los Angeles, Quinton C. Johnson, Torrance, and Joseph E. Straub, Manhattan Beach, Calif., assignors to North American Aviation, Inc.

Application May 28, 1949, Serial No. 95,896

10 Claims. (Cl. 89—37.5)

1

This invention pertains to gun blast doors and mechanism for operating the same.

The invention more particularly pertains to an arrangement for opening the doors quickly and for normally returning them within a predetermined period of time after cessation of firing of the gun.

It is an object of this invention to provide a closure member for gun ports and like openings, and means for automatically operating these members.

It is also an object of the present invention to provide means for automatically moving the closure members to open position upon initiation of firing, and to return them to the closed position upon cessation of firing, all without requiring the pilot's attention.

It is also an object of the present invention to provide time delay means incorporated in the door control circuit to avoid premature closing of the doors when the temperature of the guns has become elevated to a point where the possibility exists of inadvertent firing through heating effects.

It is a further object of the present invention to provide actuating mechanism for gun port doors which is positive in action, rugged in construction, and controllable in a reliable manner.

Other objects of the present invention will be apparent from the following description taken together with the accompanying drawings, in which:

Fig. 1 represents a schematic arrangement, partly in section, of a door in the closed position with its associated actuation mechanism;

Fig. 2 illustrates the door in open position;

Fig. 3 is a top plan view of the door actuating unit;

Fig. 4 is a sectional view taken on line 4—4 of Fig. 3; and

Fig. 5 is a circuit diagram illustrating the subject arrangement.

Referring to the drawings, the arrangement comprises a door 1 pivotally mounted at 2 on the exterior surface of an aircraft and movable to and from a closed position by means of lever arm 3. The arm 3 is operated by a mechanism presently to be described. Such mechanism includes a threaded fitting 4 pivotally mounted between the bifurcated arms of lever 3, such fitting receiving a bolt 5 which is splined to a rotatable shaft 6. Stop members 7 and 8 serve to limit the movement of lever 3. Shaft 6 is operated by means of a gear wheel 9 integral therewith and engageable by worm 10 opera-

2

tively connected to shaft 11 which is driven by a source of power (not shown). Shaft 11 is movable to a position where worm 10 is out of engagement with gear 9 by means of a rotary type solenoid 12 pivoted at 13 and having an arm 14 pivoted thereto at 15 which in turn is pivotally connected at 16 to housing 17 carrying shaft 11 and worm 10. Accidental disengagement of the worm from the worm wheel is prevented by an over center arrangement, as represented by a straight line between points 15 and 16 on the arm 14 with respect to the center of rotation 13 of the solenoid 12.

A spring 18 returns the solenoid arm and worm 15 to gear-engaging position upon de-energization of the solenoid. Housing 17 is pivotally mounted at 19 on bracket 20. Shaft 11 is mounted in housing 17 by means of pivotal bearing 21. A self-aligning bearing 22 supports the other end 20 of shaft 11 on bracket 23 which forms a part of the frame. A pin and slot arrangement at 24 has sufficient lost motion to permit alignment of shaft 11 with shaft 25, and to permit shaft 11 to pivot upon bearing 21 when housing 17 is moved about its pivot 19 to disengage worm 10 from gear 9. Torque spring 26 is operatively connected at one end to shaft 6 and at the other end to the frame to constantly urge the doors into open position so that upon disengagement of worm 10 with gear 9 the doors will immediately move to open position.

The door actuator unit is arranged to provide positive retention of the door 1 in both open and closed positions. The door is retained in the open position to prevent displacement through blast effects during firing and is retained in the closed position against air loads during flight. The means for accomplishing this is provided by the stops 7—8 which are positioned so as to provide an over-center action 35 with respect to a line drawn between the pivot point 27 of the block 4 and the pivot 28 of the door fitting as the shaft 6 rotates the arm 3.

The actuator unit is further designed to avoid 45 damage to the mechanism which may readily occur from the corrosive effects of the hot gases and the blast forces during firing. To this end only the chamber 29 in which the actuator arm 3 is positioned is exposed. This chamber is 50 completely sealed precluding the possibility of the remainder of the mechanism being affected by the blast gases with the resultant possibility of malfunctioning or failure.

The door 1 is supported upon a housing 55 which forms a forward continuation of the gun

blast tube (indicated in phantom) and provides means for excluding the blast gases from the adjacent portions of the structure. The housing is sealed except for the aperture 51 through which the arm 3 extends. When the door is open a port is provided at 52 through which the gun may fire.

A deflector plate 53 is provided upon the arm 3, serving to deflect outwardly any projectile fired when the door is closed. The door is made of a frangible material sufficiently durable for normal operation but designed to give way under the impact of a projectile. The deflector plate is arranged to direct the bullet against the door rather than permitting it to be indiscriminately deflected, rupturing the housing and damaging the adjacent structure and other equipment.

Power is supplied to the door-closing mechanism through the shaft 25, to move the door 1 to close port 52. A friction clutch 54 is interposed between the power source and shaft 25, arranged to slip when the door is fully closed until the power provided to drive the closing mechanism is discontinued.

The gun muzzle door-opening and -closing circuits are energized when the selector switch 30 is switched on and as the two-stage gun-firing switch 31 reaches the first position, the second stage serving to actuate the gun-firing mechanism. Engagement of the switch 31 energizes relay 32 which momentarily supplies current to relay 33 to complete the circuit 34 to energize the door solenoid 12 to release the door, allowing it to move to open position. The relay 33 is de-energized when the circuit is broken at relay 32, interrupting circuit 34.

The relay 32 operates a double pair of contacts, the second pair 36 serving to interrupt the circuit to the door-closing actuator 35, to be fully explained later. Upon cessation of firing, when the switch 31 is opened, relay 32 is de-energized allowing the contacts 36 to reengage to complete the circuit supplying power to a timer unit indicated at 37. The timer unit provides for a fixed time period to permit the gun to cool. The timer unit includes a constant speed motor 38 which drives a pair of cams 39-40. Cam 39, at the end of the delay period, closes the switch 41 to energize the relay 49 to complete the circuit to the door-closing actuator 35 which drives shaft 25. The cam 40 subsequently opens a switch 42 to de-energize the relay 43 to interrupt the circuit supplying power to the timer motor 38 upon completion of the door-closing operation.

The timer circuit is controlled through relay 43, and a limit switch 44 on the door 1 prevents the relay 43 from being energized except when the door is in the open position. To prevent the door limit switch 44 from interrupting the timer cycle prematurely, the line 45 serves to maintain the relay 43 in energized condition and insures the continuing operation of the motor 38 until the switch 42 is opened by the cam 40.

When firing the guns while the ship is on the ground, as in testing or boresighting, it is necessary to prevent the doors from closing at the end of the usual timing period since the cooling rate is much slower than with the air blast encountered during flight. For this purpose a ground-air transfer relay 46 is provided to interrupt the circuit supplying current to the timer 37. A switch 47 which may be carried by, for instance, the landing gear for actuation by the weight of the ship when on the ground is

opened to prevent the relay 46 from becoming energized.

A manual door-closing switch 48 is provided for the convenience of the ground crew and after an adequate cooling period has elapsed the switch may be used to energize the relay 42 to complete the circuit supplying current to the door-closing actuator 35. In the event the doors are left open after ground operation the transfer relay 46 will be energized immediately upon the closing of the switch 47 upon takeoff. The normal operation of the timer unit 37 will then take over, completing the closing operation after the usual delay.

As a safety measure a momentary delay is provided to insure the door reaching its fully opened position prior to the actual firing of the gun. When the firing switch 31 reaches the second position a relay 55 of the time delay type is energized. The relay 55 closes the circuit 56 which energizes the gun firing solenoid. The relay 55 has a very short time delay characteristic, in the order of 50 milliseconds.

Although the invention has been described and illustrated in detail, it is to be clearly understood that the same is by way of illustration and example only and is not to be taken by way of limitation, the spirit and scope of this invention being limited only by the terms of the appended claims.

We claim:

1. In an aircraft having a port opening for a gun, a door for said opening and actuating means for said door, said door being made of material which is sufficient to withstand pressure to which it is subjected in flight, but is frangible upon impact of a bullet, link means connecting said door to said actuating means, said link means being located in the line of fire of the gun when the door is in closed position, and a plate on said link for deflecting any inadvertently fired bullet to the frangible door.

2. In an aircraft having a port opening for a gun, a door for said opening, actuating means for said door, said actuating means comprising spring means, motor-driven worm and gear means for tensioning said spring means, a rotary solenoid for moving said worm into and out of engagement with said gear, link means for connecting said rotary solenoid to said worm, and an over-dead-center arrangement for locking said worm in engaging position with said gear.

3. In an aircraft having a port opening for a gun, a door for said opening and actuator means for said door, said actuator means comprising a rotatable shaft driven by a pilot-controlled source of power, a bolt fixed to said shaft to rotate therewith, a fitting on said bolt, and a lever pivotally connected at one end to said fitting and at the other end to said door, the pivotal connection of said lever to said fitting being an over-dead-center arrangement for locking the door in either its open or closed position.

4. In an aircraft having a port opening for a gun, a door for said opening, and actuator means for said door, said actuator means comprising a pilot-controlled driving gear, a driven gear operatively associated with said driving gear, means operatively connecting said driven gear and said door, spring means constantly urging said door to open position, and means for disengaging said driving gear from said driven gear to permit said spring to open said door.

5. In an aircraft having a port opening for a gun, a door for said opening, and actuating

means for said door, said actuating means including a driving gear and a driven gear for urging said door into closed position, means for urging said door into open position, and means for disengaging said driving gear from said driven gear to permit operation of said door opening means.

6. In an aircraft having a port opening for a gun provided with a firing mechanism, a door for said opening, actuating means for said door, means connected to said firing mechanism for opening said door upon actuation of said firing mechanism to initiate firing of said gun, and time delay means connected to said firing mechanism and said door-actuating means for preventing closing of said door for a predetermined period of time after cessation of firing.

7. In an aircraft having a port opening for a gun, a door for said opening, and actuating means for said door comprising spring means constantly urging said door to open position, motor-driven worm and gear means for closing said door and tensioning said spring, and means for disengaging said worm from said gear for permitting said spring to open said door.

8. In an aircraft having a port opening for a gun, a door for said opening, actuating means for said door, means for preventing operation of said actuating means, and locking means on said aircraft connected to said operation-preventing means and actuated by the weight of the aircraft when on the ground to prevent closing of said door when said aircraft is on the ground.

9. A device as recited in claim 8 and further

including means responsive to operation of said locking means for automatically closing said door when said aircraft is airborne.

5 10 15

10. In an aircraft having a gun provided with a blast tube, a forward extension on said blast tube, an opening in said extension for said gun, a door for said opening, lever means pivotally connected to said door, a housing for said lever means opening into said extension, means for actuating said lever to operate said door, and means for sealing said actuating means with respect to said housing.
